UNITED STATES PATENT OFFICE.

CHARLES ALGERNON PARSONS, OF NEWCASTLE-UPON-TYNE, ENGLAND.

STEAM-TURBINE.

No. 858,205.

Specification of Letters Patent.

Patented June 25, 1907.

Application filed July 12, 1906. Serial No. 325,881.

To all whom it may concern:

Be it known that I, CHARLES ALGERNON PARSONS, a subject of the King of Great Britain and Ireland, residing at Heaton Works, Newcastle - upon - Tyne, Northumberland, England, have invented certain new and useful Improvements in Steam - Turbines, of which the following is a specification.

This invention relates to improvements in steam turbines and more particularly to the regulation of the expansions of the rotating and non-rotating parts of a turbine.

In steam turbines of moderate and large sizes the differences of temperature and expansion of the several parts which control the working clearances becomes very important and may cause a considerable loss of efficiency in the turbine by varying the working clearances from those predetermined. Thus the shaft and casing are bound together at the thrust block and from this point the expansion of the parts may vary considerably so that when the packings are some distance apart serious results may follow.

The object of my invention is to equalize the total expansions which govern such clearance under all conditions of working. Thus a pair of longitudinal packings consisting of say a collar working in a groove require for efficient operation to work the one within the other with a minimum of clearance and it is with the object of maintaining these clearances without making such allowances in the packing as would entail considerable loss in efficiency that the present invention is made.

The invention comprises the heating of these parts not subject directly to the heating action of the working fluid so as to maintain the predetermined clearances at radial and axial packings, or the temperature of the parts may be maintained equal by circulating oil through jackets or passages formed on or in these parts.

Referring now to the accompanying drawings which form part of my specification. Figure 1 is a section through the dummy piston end of a turbine showing a method of heating the turbine case to a temperature substantially equal to that of the rotating shaft. Fig. 2 is a view half in section on the line A A of Fig. 1. Figs. 3 and 4 are views similar to Figs. 1 and 2, (Fig. 4 being a section on the line B B of Fig. 3) and show a modified form of the invention. Figs. 5 and 6 illustrate a further modification, Fig. 5 being a view similar to Fig. 1 while Fig. 6 is a

section on the line C C of Fig. 5. Figs. 7 and 8 are sectional side and cross elevations, respectively, of a form of the invention in which the heat is applied to the rotating part. Fig. 7^a is a section on the line D D of Fig. 7.

In carrying out this invention in the manner shown in Figs. 1 to 6 of the accompanying drawings, I utilize the expansion of the shaft by the heat given up by the steam in the packing gland and I provide a jacket in the turbine casing, which jacket may be supplied with steam at atmospheric pressure or at a pressure equal to that in the usual lantern space or spaces in the gland. In Figs. 1 to 6, three constructions are shown.

In Figs. 1 and 2 the steam supplied heats only the lower part of the turbine case where the quantity of metal is greatest, this heat being carried by conduction to the upper part of the case. The turbine shown here is of the general form which is commonly used on land. The usual dummy pistons, a, a', a'', are shown formed in one with the turbine drum, c, which is mounted on the turbine shaft, b. The dummy pistons are provided with the usual steam packings x and the shaft is provided with the well known form of rotary packing gland, d. A passage, e, leads to the condenser and carries off any steam that may have leaked past the dummy piston, a, as is usual in steam turbines of this type. For the purpose of equalizing the expansion of the casing and the shaft I find in this form of turbine that it is necessary to heat the turbine casing. To do this a pipe connection, f, is provided which is connected to some convenient source at about atmospheric pressure, whereby the steam jacket is supplied with steam arranged to heat the lower part of the turbine case. In this form the jacket covers the lower half of the end casing and communicates freely with the lantern space, h, of the packing gland, d.

A pipe, k, drains the lantern space, h. In the left of Fig. 1 I have indicated the outside bearing, j, which is situated between the low pressure end of the turbine and a thrust block at t.

In Figs. 3 and 4 the usual turbine parts are substantially similar to those in Figs. 1 and 2. In this case, however, the steam jacket, g, extends over the whole of the end casing and thereby further assists in attaining the results aimed at by this invention, especially in the case of large turbines. In Figs. 3 and

4 the jacket, *g*, is connected to a suitable steam space through a pipe *f*, located in the bottom of the case. The lantern space, *h*, in the gland, *d*, is connected to the steam jacket, *g*, through the opening, *m*. As in the form described with reference to Figs. 1 and 2, the pipe, *k*, acts as a drain to the lantern space. It will be recognized also that in this form instead of the lantern space, *h*, and the jacket, *g*, being common they are fed in series with the same steam.

5 Figs. 5 and 6 show another modification in which the jacket extends over the whole of the end casing. The difference between this 15 form and that shown in Figs. 3 and 4 is that the lantern space, *h*, and the jacket *g* are separately connected to steam spaces. The opening, *f*, leads to the steam jacket, while the opening, *o*, leads to the lantern space, *h*. 20 In this form it is possible to supply the jacket and lantern space with steam at different pressures or the same as desired.

25 Figs. 7 and 8 illustrate a method of applying my invention to a turbine of the type which is usually applied in marine work. In this form of turbine the expansion of the non-rotating parts tends to diminish the working clearance so that it becomes necessary to heat the rotating parts. This is done in the 30 form illustrated by providing the end wheel of the turbine drum with hollow spokes, *p*, the inner ends, *q*, of which register with radial holes, *r*, in the shaft. These radial holes, *r*, communicate with a central hole, *s*, in the 35 shaft while the hollow spokes are left open at the periphery of the drum. The passages in the hollow spokes are conveniently of the flared or trumpet formation as shown in Fig. 8, the narrower part in Fig. 8 being of oval 40 section as indicated in Fig. 7^a which is a section on the line D D of Fig. 7.

The remainder of the turbine is of usual construction and will be readily understood without further description.

45 This invention may be applied in various ways to various forms of turbines and it will be understood that I do not confine myself to the particular forms of its application herein described in detail.

50 Having now described my invention, what I claim as new and desire to secure by Letters Patent is:—

55 1. In combination in an axial flow turbine a shaft, a drum and casing, a thrust block on the turbine shaft, packings arranged at various distances along the turbine shaft and drum, means for equalizing the expansions of fixed and moving parts from said thrust block, substantially as described.

60 2. In combination in an axial flow steam turbine a shaft, a drum and casing, a thrust

block on the turbine shaft, packings arranged at various distances along the shaft and turbine drum, heating chambers in the turbine casing arranged to cause equal expansion of 65 fixed and rotating parts relative to said thrust block, substantially as described.

3. In combination with an axial flow steam turbine a shaft, a drum and casing, a thrust block on the turbine shaft, labyrinth 70 packings arranged at various distances along the shaft or turbine drum, a fluid circulating chamber on the end of the turbine case the fluid circulating through which maintains a uniform expansion throughout the case shaft 75 and drum, substantially as described.

4. In a turbine of the axial flow type, means for maintaining the predetermined clearances at the packings arranged at various distances apart along the turbine drum 80 and shaft, comprising a steam jacket on the end casing, a lantern space (*h*) around the gland packing, a communicating passage between said lantern space and said jacket, substantially as described.

85 5. In a turbine of the axial flow type, means for maintaining the predetermined clearances at the packings arranged at various distances apart along the turbine drum and shaft, comprising a steam jacket on part 90 of the end casing, a lantern space (*h*) around the gland packing, a communicating passage between said lantern space and said jacket, substantially as described.

6. In a turbine of the axial flow type, 95 means for maintaining the predetermined clearances at the packings arranged at various distances apart along the turbine drum and shaft, comprising a steam jacket on the lower part of the end casing where the metal 100 is thick, a lantern space (*h*) around the gland packing, a communicating passage between said lantern space and said jacket, substantially as described.

7. In a turbine of the axial flow type, 105 means for maintaining the predetermined clearances at the packings arranged at various distances apart along the turbine drum and shaft, comprising near the packing gland where the shaft passes out of the turbine case 110 a steam jacket on the end casing, a steam connection to said jacket, an independent steam connection to the lantern space (*h*) around the packing gland, substantially as described.

115 In testimony whereof, I affix my signature in presence of two witnesses.

CHARLES ALGERNON PARSONS.
